Des. 211,908
Patented Aug. 6, 1968

211,908

ORGAN DRAWKNOB

William H. Reisner, Jr., Hagerstown, Md., assignor to The W. H. Reisner Mfg. Company, Inc., Hagerstown, Md., a corporation of Maryland

Filed Aug. 16, 1966, Ser. No. 3,481

Term of patent 14 years

(Cl. D56—2)

FIG. 2

FIG. 1

FIG. 3

FIG. 4

FIG. 5

FIG. 1 is a perspective view of an organ drawknob showing my new design;

FIG. 2 is a rear elevational view thereof;

FIG. 3 is a front elevational view thereof;

FIG. 4 is a side elevational view of the opposite side of the organ drawknob shown in FIG. 1; and

FIG. 5 is a bottom plan view of the organ drawknob shown in FIG. 1.

The dominant features of my new design are shown in solid lines in the drawings.

I claim:

The ornamental design for an organ drawknob, substantially as shown and described.
